RECEPTACLE AND SUPPORT THEREFOR

Horacio Rafael Casella, Buenos Aires, Argentina

Application October 3, 1950, Serial No. 188,144

Claims priority, application Argentina
November 15, 1949

2 Claims. (Cl. 220—1)

1

The present invention relates to a mixing device for obtaining by centrifuging combustible liquid or semi-liquid mixtures and combinations, said device being based on a receptacle for containing the substances to be mixed or combined and is characterized by a separable coupling device for coupling said receptacle to a supporting column provided with means for fixing the same to any supporting base. An essential object of this invention is to provide a device of the class referred to which comprises a mechanical combination of elements arranged in mutually cooperative relationship to provide a manually operable driving assembly for a vertical shaft carrying the stirring means for the substances contained in the receptacle. Said driving assembly comprises a train of gears which includes a toothed wheel fast on a manually operable shaft, said wheel meshing with a pinion fast on a shaft manually operable independently of the shaft of said toothed wheel. Said pinion is integral with a step-up gear wheel meshing with the pinion of a vertical shaft to which are separately and interchangeably connected the shafts carrying the stirring members for the substances to be subjected to the action of said members, said gear train forming a means whereby an axial rotary motion is transmitted to the shafts carrying the stirring members, at two speeds, one of which is accelerated by the action of the shaft carrying the toothed wheel meshing with the pinion associated with the second shaft. Said pinion together with the gear wheel integral therewith fits the high-speed rotary motion transmitting unit to the pinion integral with the shaft transmitting the axial rotary motion to the stirring members. The second slower rotary motion is provided by the second shaft the gear wheel of which causes rotation of the pinion fast on the shaft carrying the interchangeable stirring members.

The apparatus assembly is complemented by other constructional and functional features to be hereinafter described in accordance with the accompanying drawings in which a practical embodiment is illustrated by way of example, wherein:

Figure 1 is an elevation of the apparatus assembly with parts thereof in section,

Figure 2 is a plan view illustrating the assembly in cross-section along the line A—A of Figure 1, and

Figures 3, 4 and 5 illustrate the respective shafts carrying the stirring members consisting of a liquifying mixing and beating unit.

In the figures the same reference numbers and

2

letters are used to indicate similar or corresponding parts.

In the embodiment shown in the drawings the device according to the present invention comprises a receptacle *a* consisting of a hollow body of irregular lateral shape having curved portions as at *i* extending radially inwardly and forming internal ribs *2*. These ribs as may be appreciated assist in obtaining a complete agitation of the contents of receptacle *a* which, near the mouth thereof has embedded therein a ring *3* adapted to allow a hook portion *4* of a hooked arm *5* to be inserted thereunder. Hooked arm *5* is integral with a supporting column *b* and serves to support receptacle *a*. At a certain distance from hooked arm *5* there is provided on column *b* a projection *6* (Figure 1) which constitutes a lateral steadyng member for receptacle *a* and acts to maintain the same in a proper vertical position and parallel to column *b*. Near the lower end of column *b* and integral therewith there is provided a clamping device consisting of forked member *7* arranged opposite a plate *8*. Passing through plate *8* there is provided a screw *9* operable by means of a wing-nut *10* or any equivalent element and that end of screw *9* between fork member *7* and plate *8* has fast thereon a conical washer *11*. The clamping device as may be seen is provided for fixing the mixer in a suitable position on a table or the like.

At one end of column *b* there is provided a widened head portion forming a casing *12* within which a driving pinion *13* is mounted for rotation. Pinion *13* is fastened to the upper end of a driving shaft *14* guided in a boss *15* which depends from the lower surface of the aforementioned casing. Shaft *14* extends transversely of said casing and has secured thereto a sleeve *16* constituting a coupling shaft *14* and the stirring elements which will be described hereinafter.

Pinion *13* meshes with a step-up gear *18* secured on a vertical shaft *19* to which is also fastened a toothed pinion *20*. Shaft *19* extends through the outer wall of a recess *21* formed in a cover plate *22* of casing *12* and constitutes a handle receiving portion *23* for handle *24*. Toothed pinion *20* meshes with a step-up gear *25* secured to a shaft *26* mounted for rotation on coverplate *22* and extending through recess *21* to provide a handle receiving portion *27* similar to that previously described. Handle *24* may be removably mounted on either portion *23* or portion *27* of shafts *19* and *26* respectively as desired or required.

Sleeve *16* is provided with a bore *29* into which

driving shaft 14 is keyed and to the lower end of this shaft there is secured one end of a helical expansion spring 30 whilst the other end of said spring bears against the upper end of a vertical shaft 31 which projects into said bore and is provided with a pin 32 for coupling the shaft to the lower portion of sleeve 16 which for this purpose is provided with corresponding slots into which the ends of pin 32 are inserted when shaft 31 is in the correct angular position. To the lower end of shaft 31 there is secured a stirring plate 33 of hexagonal shape.

The apparatus also comprises two further shafts 34 and 35 to the lower ends of which are secured, respectively, blades 36 having a cutting edge 37 for slicing, when necessary, solidly placed in receptacle *a* and a set of rings 38 normally fixed so as to form a whipping unit. Blades 36 constitute a liquifying unit and the respective ends thereof extend obliquely one with respect to the other, the arrangement being such that it is possible to achieve a high degree of efficiency in the liquifying process.

Although in the foregoing description reference has been made to liquifying, mixing and whipping units each fixed to an individual shaft it will be understood that the arrangement may be such that these units can be removably and interchangeably attached to one single shaft. In this case, upon conclusion of the mixing or combining process, the interchange of the whipping and mixing units on the shaft may be effected without the necessity of removing shaft 31 from coupling sleeve 16 it being evident that only receptacle *a* requires removal.

The mixer operates as follows: once the receptacle *a* has been placed in position on column *b* and charged with the substances to be treated rotation of the blades at accelerated speed may be produced by placing handle 24 on handle-receiving portion 27 of shaft 26 and rotation thereof will cause the step-up gear 25 to rotate and the latter will transmit its movement to pinion 20 and hence to step-up gear 18 which is integral with pinion 20. The accelerated movement of gear 18 is transmitted to pinion 13 fast on shaft 14 to which shaft 34 or 31 is coupled as the case may be.

For whipping which requires rotation at a lower speed it is sufficient to place handle 24 on handle-receiving portion 23 of shaft 19 whereby the multiplication of speed through the action of gear 25 is eliminated.

It will be understood that while a preferred embodiment of the invention has been described, many modifications and variations may be introduced in the structural details without departing from the scope of the invention as defined in the annexed claims.

I claim:

1. In an agitating device, in combination, an elongated receptacle having a bottom wall at one end and a tubular wall, said tubular wall being formed with a plurality of spaced longitudinally extending indentations forming elongated projections on the inner surface of said tubular wall, and elongated grooves on the outer

surface of said tubular wall; a holding member secured to the outer surface of said tubular wall adjacent to the other end of said receptacle and extending across at least one of said depressed portions so that between the outer surface of said tubular wall and the inner surface of said holding member an eye is formed; a supporting column extending substantially parallel to said tubular wall and having a first projection projecting towards said receptacle and being formed with a hooked end portion extending parallel to said supporting column and to said tubular wall of said receptacle and passing into said eye so that said receptacle is supported adjacent said one end thereof on said first projection, said supporting column having a second projection spaced from said first projection and projecting towards said receptacle, said second projection being located adjacent said bottom wall of said receptacle and projecting into the one of said grooves in said outer surface of said tubular wall corresponding to said eye.

2. In an agitating device, in combination, an elongated receptacle having a bottom wall at one end and a tubular wall, said tubular wall being formed with a plurality of spaced longitudinally extending indentations forming elongated projections on the inner surface of said tubular wall, and elongated grooves on the outer surface of said tubular wall; a holding ring secured to and extending around said tubular wall adjacent to the other end of said receptacle and extending across said depressed portions so that between the outer surface of said tubular wall and the inner surface of said holding member eyes are formed; a supporting column extending substantially parallel to said tubular wall and having a first projection projecting towards said receptacle and being formed with a hooked end portion extending parallel to said supporting column and to said tubular wall of said receptacle and passing into one of said eyes so that said receptacle is supported adjacent said one end thereof on said first projection; said supporting column having a second projection spaced from said first projection and projecting towards said receptacle, said second projection being located adjacent said bottom wall of said receptacle and projecting into the one of said grooves in said outer surface of said tubular wall corresponding to said eye.

HORACIO RAFAEL CASELLA.
